GARMENT HANGER

Francis D. Dwyer, Urbana, Ohio

Application November 1, 1950, Serial No. 193,463

3 Claims. (Cl. 223—88)

1

My invention relates to garment hangers. More particularly, the invention relates to garment hangers of a two-component type of construction.

Garment hangers generally are subject to considerable service abuse, that is, they become soiled readily due to the varying nature and conditions of the garments they support, and are particularly subject to deterioration due to the hanging of wet or damp garments thereon.

Accordingly, such hangers are of relatively short service life and are not adapted to satisfactorily hold and remold a garment to the original contour of the same. Dresses and coats having padded shoulders are particularly subject to deformation when supported on ordinary hangers and are not readily reformed to their true contour when supported on hangers which have been subjected to considerable service.

Accordingly, it is desirable that a garment hanger be provided in which the portions of garment hangers supporting the shoulders of garments conform closely to the garment design. It is further desirable that the shoulder supports of the hanger which may become worn or soiled in service be readily replaceable without the inconvenience and expense of replacing the complete hanger.

It is a primary object of this invention to provide a garment hanger having shoulder supports which conform to the shoulder design of the garment to be supported.

It is a further object of this invention to provide a garment hanger having a readily replaceable shoulder support.

It is a further object of this invention to provide a garment hanger having a simple structural arrangement for the securing of a replaceable shoulder support to the garment hanger.

It is another object of this invention to provide a garment hanger of sturdy structure but sufficiently flexible to allow a limited degree of yield under the weight of a garment supported thereon.

It is an important object of this invention to provide in a two-piece construction garment hanger a structure which is quickly and easily assembled.

These and other objects of this invention are achieved by providing a garment hanger having a portion of a longitudinal member thereof recessed from other portions of the same member, to provide latches integral with the member for the reception and secure fastening of oval shaped shoulder supports for garments. Preferably,

2

though not necessary, the oval shaped supports have an integrally formed holding means for engagement with the latches.

The invention will be more clearly understood and other objects and advantages made more apparent by reference to the accompanying drawings wherein:

Figure 1 is an exploded view in perspective of a garment hanger embodying the invention;

Figure 2 is a plan view of the hanger body of Figure 1;

Figure 3 is a front elevational view of the hanger of Figure 1;

Figure 4 is a longitudinal sectional view of the shoulder support of the invention;

Figure 5 is a plan view of the shoulder support of Figure 4; and

Figure 6 is a longitudinal sectional view of another embodiment of the shoulder support of the invention.

Referring to Figure 1, the garment hanger is preferably formed of wire of a single continuous length and comprises a body member 1 having a hook portion 2 supported by a substantially vertical shank 3 and is provided with downwardly diverging portions 4, 5 having, respectively, lateral extensions 6, 7 secured thereon. The extensions 6, 7 are preferably inclined slightly to form a small angle with a horizontal plane passing perpendicularly through the vertical shank 3.

Secured to the outer end of the extension 6 is a connecting element 8 having the general shape of a U, and similarly, a connecting element 9 is joined to the lateral extension 7. Between the other ends of the connecting elements 8, 9 a longitudinal member 10 is secured which has opposing end portions 12, 13 which together with lateral extensions 6, 7 and the connecting elements 8, 9 form opposing elongated arms. Each of these

U-shaped arms lies in a plane substantially perpendicular to the vertical shank 3 and each is slightly inclined to the horizontal, as is more clearly seen in Figure 3. This longitudinal member 10 has a central portion 11 recessed from the end portions 12, 13 towards the body member 1 to form latches 16, 17, as is more clearly seen in Figure 2. These latches 16, 17 receive thereon substantially oval tubes 14, 15 which are each provided internally with collars as may be seen in Figure 4.

The latches 16, 17 may be spaced any suitable distance from the lateral extremities of the structure, but I prefer that the spacing be approximately equal to the length of the lateral extensions 6, 7 as this adds rigidity to the assembly.

The central portion of the member 10 is also preferably arched slightly and upwardly in the vertical direction to strengthen the hanger.

The collar 18 is somewhat smaller in diameter than the width between the extension 6 and the end portion 12 and consequently the wires thereof are forced slightly towards each other when the collar is passed thereover to engage the latch 16 formed between the end portion 12 and the central portion 11 of member 10. The collar 18 is of a sturdy light weight material, such as heavy paper, or a light weight wood which will sustain the slight stress imposed thereon during positioning. Similarly, oval tube 15 having collar 19 engages the latch 17 formed between the end portion 13 and the central portion 11.

The oval shaped tubes 14, 15, which may be of any suitable material but are preferably of a fibrous material such as paper, are positioned over the extremities of the garment hanger with the broad sides 20 extending in a plane substantially parallel to the plane of end portion 13 as seen in Figure 3. Thus the shorter sides 21 of the oval tubes receive substantially all the weight of the garment hung thereon. Further, this arrangement securely locks the oval tube against rotational movement on the hanger extremities.

In a further embodiment of the invention shown in Figure 6 the oval shaped tubes 22 instead of collars such as 18, 19, are provided with inwardly flanged portions 23, 24. This tube 22 is adapted to slide over the extremity of the garment hanger in such fashion that the inwardly flanged portion 23 engages the latch 16 or 17 of the garment hanger in much the same fashion as the collars 18, 19 engage the said latches. The inwardly flanged portion 24, however, is adapted to engage the extremities of the garment hanger under slight compressive stress and thus a more rigid fastening is secured. However, it will be noted that such a tube, similar to the arrangement of tubes 14, 15 may easily be withdrawn from the hanger without destruction of the same, since the tubes and the wires are in force fitting relation.

It will be understood that this invention is susceptible to modification in order to adapt it to different usages and conditions and, accordingly, it is desired to comprehend such modifications within this invention as may fall within the scope of the appended claims.

I claim:

1. A garment hanger comprising a pair of wire U-shaped members disposed in opposed relation in substantially horizontal planes and having the open ends thereof adjacent each other, said members each having first and second limb portions, an inverted Y-shaped element extending substantially vertically from said first limb

of said members and integrally secured thereto, latches inwardly extending from the free ends of said second limbs toward said first limbs at the ends thereof adjacent the extended limbs of said inverted Y-shaped element, a longitudinal element secured between the inner ends of said latches, and an oval shaped tubular member having an internal collar secured therein positioned over each of said U-shaped members, said collar of each said tubular member securely engaging a said latch.

2. A garment hanger comprising a pair of wire U-shaped members disposed in opposed relation in substantially horizontal planes and having the open ends thereof adjacent each other, said members each having first and second limb portions, an inverted Y-shaped element extending substantially vertically from said first limb of said members and integrally secured thereto, latches inwardly extending from the free ends of said second limbs toward said first limbs at the ends thereof adjacent the extended legs of said inverted Y-shaped element, a longitudinal element secured between the inner ends of said latches, and an oval shaped tubular member having an inwardly flanged portion therein positioned over each said U-shaped member, said inwardly flanged portion of each said tubular member securely engaging a said latch.

3. A garment hanger comprising a vertically extending shank portion, a pair of U-shaped arms of resilient wire disposed perpendicularly to said shank portion on opposite sides thereof, each said arm having first and second limb portions defining substantially horizontal planes, said first limbs each having one end thereof secured to said shank and the other end thereof secured to said second limbs to form a closure at the end of each said arm remote from said shank, a latch in each said second limbs between a said closure and said shank, each latch extending towards an adjacent first limb, and an oval shaped tubular member having inwardly flanged portions at each end thereof positioned over each said arm, one flanged portion of each said tubular member securely engaging a said latch, and the other said inwardly flanged portion of each said tubular member resiliently engaging said closure of each said arm.
